CLAIM

The ornamental design for a bicycle chainring as shown and described.

DESCRIPTION

FIG. 1 is a front and left side perspective view of a bicycle chainring showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the bicycle chainring shown in dashed lines illustrate environment and form no part of the claimed design.

1 Claim, 5 Drawing Sheets
